MONITOR FOR FILAMENTARY MATERIAL

Robert M. Brink, Pelham, N. Y., assignor to Deering Milliken Research Trust, New York, N. Y., a nonprofit trust of New York

Application November 13, 1947, Serial No. 785,661

8 Claims. (Cl. 28—64)

1

The present invention relates to the manufacture of yarn and more particularly to the inspection of yarn for detection of irregularities, hereinafter called slubs, therein and comprises a novel mechanical yarn monitoring device which is simple of construction, positive in action and operates, independently of the rate of travel of yarn therethrough, to break the yarn when the diameter thereof exceeds a predetermined value over a predetermined length.

There are various known mechanical devices, called slab catchers, now in use in the textile industry, each of which operates to cut or break yarn whenever the diameter thereof exceeds a value for which the device is set. These devices respond only to the diameter of the yarn and do not distinguish between slubs of different length. As very short slubs are ordinarily not objectionable, such known devices cut or break the yarn more often than is necessary. This results in an excess of knots in the yarn and in undue labor on the part of the operator who must remove the slab from one end of the yarn after severance by the device and tie the severed ends together.

There has thus been a decided need in the industry for a slab catcher that could distinguish between long and short slubs. As slab catchers are used at various stages of yarn manufacture, a great number are required in any one mill. Hence it is important that the device be of simple and economical construction, that it operate without failure and that it be simple of adjustment and of relatively long life.

The monitor device of the present invention meets these and other desiderata. It discriminates between short and long slubs, allowing the former to pass therethrough and breaking the yarn upon occurrence of the latter. It is of economical and durable construction, has only one moving part and may be readily adjusted for accommodation of yarns of different average diameter. Moreover the device of the invention operates to discriminate between slab lengths independently of the rate of yarn travel therethrough.

The new slab catcher comprises but two essential parts, a plate over which the yarn travels and a generally short legged U-shaped member pivotally mounted above the plate with its legs depending and positioned to be successively engaged by slubs in the yarn. This device permits passage therethrough of slubs of a length less than the spacing between the ends of the legs as such slubs merely rock the pivoted mem-

2

ber during passage through the device. When slubs longer than the spacing between the legs enter the device, they are held therein with consequent breakage of the yarn.

5 For a better understanding of the invention reference may be had to the accompanying drawing of which:

Figs. 1 to 6 inclusive are diagrams explanatory of the principle of operation of the device of 10 the invention and illustrating how the device discriminates between long and short slubs;

Figs. 7 and 8 are sectional and side views respectively of a monitor device embodying the invention, Fig. 7 being a section on the line 7—7

15 of Fig. 8;

Fig. 7a is an enlarged sectional view of the pivoted member of the device of Figs. 7 and 8; and

Fig. 9 is a sectional view showing an alternative construction of pivoted member.

20 In Figs. 1 to 6 inclusive the essential parts of the device of the invention are diagrammatically illustrated as comprising a fixed platform 2 and an inverted U-shaped member 4 pivotally supported above the platform 2, by a pin 6. The

25 distance above the support 2 at which the member 4 is mounted depends upon the desired minimum diameter of slab to be detected, as will be apparent as the description proceeds. Yarn, indicated at 8, travelling in the direction of the arrow, moves over the platform 2 beneath the legs 4a and 4b of the member 4. It will be understood that the yarn is moved by any suitable means. The travel of the yarn may be assumed to be part of one of the normal operations in a

30 mill. For example, the yarn may be in passage from a bobbin to a spooler or other winder and therefore travelling at a relatively high rate of speed. The two sections of the yarn 8 which are indicated at 10 and 12 represent slubs of the same diameter but of different length. It will be appreciated that the slubs have been purely diagrammatically illustrated as an aid in the understanding of the operation of the new device and that no attempt has been made to illustrate

35 in the drawings the actual appearance of a slab. Slub 10 is shorter than the distance between the lower ends of legs 4a and 4b and will pass through the device, whereas slab 12 is longer than this distance and will be detected. As the short slab 40 10 proceeds through the monitor device, the advancing end of the slab engages leg 4a and rocks member 4 counterclockwise into the position shown in Fig. 2. The advancing end then engages leg 4b and rocks the member 4 clockwise into the position shown in Fig. 3. Due to the

short length of slab 10, the trailing end of the slab has cleared leg 4a by the time the advancing end engages leg 4b and hence the clockwise movement, which permits egress of the slab from the device, is not limited by the slab. Fig. 4 shows slab 10 leaving the device, slab 12 approaching the device and member 4 returned to normal position. When the advancing end of the long slab 12 engages leg 4a, as shown in Fig. 5, it rocks the member in a counterclockwise direction in the same way as did the short slab 10. However, in the case of the long slab, when the advancing end engages leg 4b, member 4 cannot rock sufficiently clockwise to permit the slab to pass under leg 4b because the trailing end of the slab has not cleared leg 4a as shown in Fig. 6. Thus the yarn is arrested at leg 4b and the tension in the yarn causes breakage as indicated at 16 in Fig. 6.

The essential elements of the new device and the operation thereof have now been described with reference to the diagrams of Figs. 1 to 6. In Figs. 7, 7a and 8, to which reference may now be had, a specific construction of a monitor device embodying the invention is illustrated. As shown, the base plate of the device comprises a block 20 of rectangular cross section having rounded edges 20' for travel of yarn thereover during ingress to, and egress from, the device. The block 20 may be, for example, of cold rolled steel and the surface thereof over which the yarn travels is preferably polished. The pivotally supported member of the device is indicated at 40 and its depending legs at 40a and 40b. A pin 60, the ends of which are rotatably mounted in a bracket or frame 24, supports the member 40 above the block 20; suitable spacing members 25 being provided between the ends of the member 40 and the frame. Frame 24 is secured to the block 20 by machine screws 26 which pass through an elongated slot 28 in frame 24 and into threaded holes in the block 20. With this arrangement the spacing between the member 40 and polished surface of the block 20 may be adjusted in accordance with the average diameter of the yarn and minimum diameter of slab to be caught.

The operation of the device of Figs. 7 and 8 will be clear from the description already given in connection with Figs. 1 to 6. If the direction of yarn travel is from right to left (as viewed in Fig. 7) then slabs in the yarn of a diameter greater than the distance between the surface of block 20 and the lower edge of leg 40a when member 40 is in the neutral position illustrated in the drawing, will rock the member in a counterclockwise direction. Slabs of a length less than the spacing between the legs 40a and 40b, indicated as "d" in Fig. 7a, will rock the member in a clockwise direction upon engagement with leg 40b and pass on through the device while slabs longer than d will be blocked by leg 40b. With the particular shape of member 40 illustrated in the drawings, slabs of a length less than d will be passed and those of a length greater than d will be caught irrespective of whether the yarn travels from right to left, or from left to right (as viewed in Fig. 7) as the member 40 is unsymmetrical about the vertical plane intermediate the legs 40a and 40b.

In order that the initial direction of rotation of the member 40 upon engagement of a slab with a leg be in a direction to permit entry of the slab into the space between the legs the distance "a" (see Fig. 7a) between the plane

passing through the tips of the legs and the parallel plane through the axis of rotation of member 40 should be small, preferably less than $d/2$ and the outer surfaces 41 of the legs should be inclined to the vertical through a substantial angle. The particular angle of inclination depends upon the relative dimension of "a" and "d" and should be such that when the surface is engaged by a slab, the component of force normal to the surface will tend to rotate the member in the proper direction. If the device is to be used for one direction only of yarn travel, the inclination of the surface 41 on the leg last to be encountered is immaterial.

The pivoted member of the device should be of relatively hard material. The lower edges of the legs need not be cutting edges, as the operation of the device in eliminating slubs longer than d does not require actual cutting of the yarn. If desired the inner face of one or both legs could be shaped to increase the "jamming" action when engaged by a long slab. Such construction is illustrated in Fig. 9 wherein the leg 40b' of the pivoted member 40' has an inner plane face 42 disposed at right angles to the direction of yarn travel. With yarn travel from right to left of the drawing, such shape of leg 40b' provides a firm grip on the forward end of a long slab and enhances the jamming action of the device. Leg 40a' could be similarly shaped if the device is to operate independently of the direction of yarn travel.

Although in the particular embodiment of the invention illustrated in the drawings the lower edge of the legs are equidistant from the axis of the pin 60 and, when the member is in neutral position, lie in the same horizontal plane, this construction of the pivoted member while increasing the range of short slab diameter that can pass through the device, is not essential, nor is it essential that the member be nicely balanced so as to tend to return to a position where the tips of the legs are equidistant from the surface of the block. So long as the pivoted member is relatively light and free to rock when engaged by a slab, the device will operate satisfactorily. Hence no precision machinery is required in production nor fine adjustment in installation. As the pivoted member is engaged only when a slab occurs in the yarn, but little wear will be experienced by the edges of the legs. Such little wear as might occur can be readily reduced by causing the yarn to traverse in conventional manner back and forth along the legs if desired but in view of the relative low cost of production of the pivoted member, it is simpler to replace the member when worn to too great an extent. The pivoted member can be readily removed for replacement by withdrawal of the pin 60 from the device as will be apparent to those skilled in the art. In the same manner, if it is desired to change the minimum length of long slab to be caught, a pivoted member having the desired spacing of legs can be readily inserted in the device. If change in the minimum diameter of long slab to be caught is desired, the screws 26 may be loosened and the frame 24 moved up or down as desired to adjust the spacing between the upper surface of the block and the legs of the pivoted member.

From the foregoing description of the invention and of one specific embodiment thereof, it will be apparent that the yarn monitor of the invention is an efficient and practical device that can be constructed at minimum cost and that will operate, independent of the rate of yarn

travel therethrough, to discriminate between short unobjectionable slubs and longer slubs, eliminating the latter and passing the former. Obviously various changes, some of which have been indicated hereinbefore, could be made in the construction and operation of the device without departing from the spirit of the invention and various conventional yarn handling devices could be employed in conjunction therewith. For example yarn tensioning devices could be, and probably would be, inserted in the yarn path on one or both sides of the monitor device and conventional means responsive to yarn tension could be associated with the monitor for stopping the spooler or other winding device causing the travel of the yarn when the yarn breaks at egress from the monitor. Such conventional yarn handling devices have not been illustrated in the drawings as they are well known in the art and form no part of the present invention.

In the foregoing description and in the appended claims, the term "slub" is intended to mean a length of filamentary material that is oversize and the term "yarn" is intended to mean any textile filamentary material, whether natural or artificial, whether of continuous or of discontinuous fibers and whether of one or of a plurality of filaments.

The following is claimed:

1. A yarn monitor device for detection of slubs comprising in combination, a plate having a surface for travel of yarn thereover, an oscillatable member mounted adjacent said surface, said member having spaced portions positioned to be successively engaged by a slub during travel of yarn over said surface and between said surface and said portions, said portions being so located on said member with respect to its axis of oscillation that successive engagements with a slub tend to rock the member in opposite directions about its axis whereby slubs longer than the spacing between said portions are detected.

2. A yarn monitor device comprising in combination a fixed member having a substantially horizontal surface for travel of yarn thereover and a member having a cross section substantially of the shape of an inverted relatively short legged U pivotably supported above said surface with the depending legs thereof positioned to be successively engaged by a slub during travel of the yarn over said surface and between said surface and the ends of the legs whereby a slub shorter than the spacing between the legs of the U-shaped member successively rocks the member in opposite directions during passage through the device while a slub longer than such spacing rocks the member in one direction upon engagement with the leg first in its path but is stopped upon engagement with the other leg.

3. A yarn monitor device comprising in combination a fixed member having a substantially plane surface for passage of yarn thereover, a member having a pair of integral spaced depending legs and means for supporting said last mentioned member adjacent said surface for oscillation about an axis intermediate said legs and

substantially parallel to said surface whereby each slub in the yarn of a diameter greater than the average distance between said surface and the base of said legs successively engages said legs, slubs shorter than the spacing between said legs successively rocking said supported member in opposite directions and slubs longer than such spacing rocking said supported member upon engagement with the leg first encountered and being arrested by the other leg.

4. The device according to claim 3 wherein the leg to be first engaged by slubs during passage of yarn through the device has a surface inclined to the direction of yarn travel at an angle so related to the length of the leg and the distance from the base of the leg to the axis of oscillation of the supported member that a force normal to said inclined surface of the leg produces a couple tending to rotate the supported member in a direction to move the base of the legs counter to the direction of travel of the yarn.

5. The device according to claim 3 wherein the leg last to be engaged by a slub has a substantially vertical slub engaging surface.

6. The device according to claim 3 wherein one half the spacing between the legs is greater than the distance between two parallel planes, one of which passes through the axis and the other of which is tangent to the base of the legs.

7. A yarn monitor device for discriminating between long and short slubs in yarn comprising in combination a fixed support having an upper flat surface for passage of yarn thereover, a framework comprising an upright member secured to said support, a horizontal arm secured at one end to said upright member and extending over said surface, a depending section secured to the other end of said arm, a pin horizontally disposed with its ends supported in aligned holes in said upright member and in said depending section, and a member carried by said pin and having depending spaced legs terminating above said surface for passage of yarn thereunder, slubs on the yarn successively engaging said legs and rocking said pin carried member about the axis of the pin, whereby slubs of a diameter greater than the average distance between the surface and the extremities of said legs and longer than the spacing between the legs are stopped upon engagement with the second leg in their path.

8. The device according to claim 7 wherein said upright member is adjustably secured to said fixed support whereby the average distance between said surface and the extremities of said legs may be varied.
